UNITED STATES PATENT OFFICE.

REUBEN B. BENJAMIN AND JAMES M. CURLESS, OF CHICAGO, ILLINOIS, ASSIGNEES TO
BENJAMIN ELECTRIC MANUFACTURING COMPANY, OF CHICAGO, ILLINOIS, A COR-
PORATION OF ILLINOIS.

MACHINE FOR MAKING TINSEL.

1,377,548.

Specification of Letters Patent. Patented May 10, 1921.

Application filed May 13, 1920, Serial No. 381,189. Renewed March 19, 1921. Serial No. 453,706.

To all whom it may concern:

Be it known that we, REUBEN B. BENJAMIN, a citizen of the United States, residing at Chicago, in the county of Cook and State 5 of Illinois, and JAMES M. CURLESS, a citizen of the United States, residing at Chicago, in the county of Cook and State of Illinois, have invented certain new and useful Improvements in Machines for Making Tinsel, 10 of which the following is a full, clear, concise, and exact description, reference being had to the accompanying drawings, forming a part of this specification.

This invention relates to manufacture of 15 tinsel, small magnet wire, and the like. The tinsel referred to comprises a core consisting of cotton or other thread, having a metallic filament wound around it. While the metal filament may be of any size desired in cross- 20 sectional form, the filament or "ribbon" (as it is usually called) is ordinarily .013 inch wide and .0007 inch thick.

One of the objects of our invention is to 25 provide a machine of the type indicated above which will be efficient and durable in operation and simple in construction.

A further object of our invention is to 30 provide an improved machine of the type indicated which will be less apt to break the filament than the machines heretofore in use.

A further object of our invention is to 35 provide certain safety features.

Further objects will appear from the detailed description to follow and from the 35 appended claims.

In the drawings in which one embodiment of our invention is shown;

Figure 1 is a side elevation of a machine embodying our invention, parts being broken 40 away to show the interior construction;

Fig. 2 is an axial section through the winding head and turbine;

Fig. 3 is a horizontal, transverse section substantially on the line 3—3 of Fig. 2;

Fig. 4 is an axial section through the upper part of the spindle;

Fig. 5 is also an axial section through the upper part of the spindle on a different plane from that of Fig. 4; and

Fig. 6 is a section substantially on the line 6—6 of Fig. 2.

The construction shown in the drawing comprises in a general way, means for advancing a thread or core longitudinally

without rotating it, and means for wrapping 55 a second thread helically about said first thread, as said first thread is advanced. The first thread or core is advanced longitudinally through a rotatable tubular spindle, on which rotatable tubular spindle is mounted 60 the winding head, in which winding head is inclosed a spool of the filament which is to be wrapped around the first thread. The winding head carries a "flier" or filament guide, through which the filament passes, 65 which flier or filament guide causes the filament to be wrapped helically around the core as the winding head rotates. A fluid pressure turbine, such as a steam turbine or air turbine, directly connected with the spindle may be used for driving the machine. Suitable means are provided for causing the core to be advanced longitudinally, a construction shown for this purpose comprising 70 a capstan provided with a worm drive from 75 the rotatable tubular spindle.

Referring now to the drawing in detail, the means for advancing the thread or core 10 longitudinally through the rotatable tubular spindle 11, comprises a capstan 12, 80 about which the core 10 passes, the capstan 12 being driven from the tubular spindle 11 by means of the worm wheel 13, which meshes with the worm portion 14 of the tubular spindle, the worm wheel 13 being secured 85 on the shaft 15, on which the capstan 12 is also secured. Suitable guide pulleys 16 (see Fig. 1) may be provided for guiding the core 10 from the tubular spindle 11 through the capstan 12. The tubular spindle 11 itself may be driven from a turbine wheel 17 (Figs. 2 and 3) to which fluid is supplied through a plurality of nozzles 18. A suitable casing 19 is provided for the turbine wheel 17, the casing 19 being closed by 90 a cover 20, secured to the casing 19 by means of screws 21. Suitable anti-friction bearings 22 may be provided for the rotatable tubular spindle 11.

The filament 23 which is to be wound helically about the core 10 may be unwound from a spool or cop 24, which may be slipped on over the upper end of the tubular spindle 11, and may be free to rotate with respect to said tubular spindle. The filament 23 100 is led from the spool 24 through a flier or filament guide 25 which is secured to a conical housing member 26, which housing mem-

ber is secured to rotate with the tubular spindle 11.

For guiding the core 10 at the point where the filament 23 is being wound about it, a 5 grooved guide 27 (Figs. 4 and 5) is provided, which is recessed as indicated at 28 and 29 to provide clearance for the filament 23.

In order to confine the filament 23 at the point where it is being wound about the core 10, a tubular confining member 30 is provided having a comparatively large opening 31, through which the filament 23 passes to be wound about the core 10.

The winding head 26 rotates at a very 15 high speed, sometimes as high as 40,000 revolutions per minute. In order to lessen the air resistance to be encountered by the filament 23 as the winding head is being driven at this very high speed, a conical 20 sheet metal cover 32 is provided having a flange or skirt portion 33, which fits down over the upper edge of the cup-shaped housing 26, and having an opening 34 at its upper end, which is just large enough to fit 25 snugly over the restraining member 30. The top 24 and that part of the filament 23 between the top and the point where the filament is wrapped around the core is thus entirely inclosed by the housing member 26 30 and cover 32.

In order to hold the cover 32 securely in position on the housing 26 a pair of spring latch members 35 are provided, these latch members being in the form of leaf springs 35 secured at 36 to the restraining member 30, the upper ends 37 of these leaf springs engaging over the upper edge 38 of the cover 32 to hold it in position.

The fact that the cover 32 is made conical 40 in shape and tapers upwardly causes the air current created by the rotation of the cover to assist in holding the cover in place. The cover 32 as it rotates tends to throw the air in contact with it outwardly, after 45 the manner in which water is thrown off a grindstone and this causes a current of air to flow downwardly over the cover, which air current will tend to hold the cover 32 in place and thus assist the latch fingers 35.

50 Centrifugal force also tends to throw the spring latch fingers 35 outwardly so that the faster the winding head is rotated, the more securely the cover 32 will be held. The fact that the housing member 26 is made conical 55 in shape, tapering upwardly from the lower flange 39 of the cop 24, to the point where the flier 24 is attached, results in lessening the moment of inertia of the casing 26 as it rotates, which is desirable, as the less the 60 moment of inertia the less is its disturbing effect on the rotation of the rapidly rotating spindle 11. The flier 25 itself is located substantially midway between the lower flange 39 and the upper flange 40 in the cop 65 24, which is the proper location for it, to

70 permit the filament to unwind properly from one end to the other of the cop. The tapering surfaces of the housing member 26 and of the conical cover member 32 form suitable supports for the filament 23, which 75 may be thrown against these supporting surfaces by the centrifugal force occasioned by the very high speed of rotation. These conical surfaces form smooth supporting surfaces over which the filament passes from the cop 24 to the point where the filament 80 is wound onto the core 10.

The operation of the device has been outlined in connection with the description of the construction. It is briefly as follows: 85 The cop 24 is slipped over the tubular spindle 11, and the core 10 is threaded up through the tubular spindle 11, and over the guide pulleys 16 and is wrapped around the capstan. The end of the filament 23 is then 90 threaded through the flier 25 and brought up and secured to the core 10. The turbine is then put into operation, to cause the winding head 26 to rotate and the capstan 12 to revolve. As the capstan 12 revolves it causes 95 the core 10 to be advanced longitudinally, and as the winding head is revolved it causes the flier 25 to revolve also and causes the filament 23 to be wound helically about the core 10.

Having thus described our invention, what we claim as new and desire to secure by Letters Patent of the United States is:

1. A machine comprising means for advancing a thread longitudinally, and means for wrapping a second thread helically around said first thread as said first thread is advanced longitudinally, said wrapping means comprising a rotatable winding head, rotatable about the axis of said first thread, 100 means for supporting a spool of said second thread coaxially with said first thread, a rotatable housing for said spool, and means rotatable with said housing for guiding said second thread as it is unwound 105 from said spool, said housing being conical and tapering upwardly from the lower periphery of the spool to the thread guiding means.

2. A machine comprising means for advancing a thread longitudinally, and means for wrapping a second thread helically about said first thread as said first thread is advanced longitudinally, said wrapping means comprising a rotatable winding head, and a 115 rotatable tubular spindle through which said first thread is advanced, said winding head being secured to said tubular spindle to rotate therewith, said winding head comprising a housing member and a cover for 120 said housing member, means for mounting a spool of said second thread to rotate with respect to said spindle within said housing member and cover, said wrapping means comprising also means for guiding said sec- 125 130

ond thread, at the point where it is about to be wound about said first thread, and means for guiding the thread between the point where it leaves the spool and said 5 first guide means, said cover being conical in form and tapering from said second guide means to said first guide means.

3. A machine comprising means for advancing a thread longitudinally, and means 10 for wrapping a second thread helically about said first thread as said first thread is advanced longitudinally, said wrapping means comprising a rotatable winding head and a rotatable tubular spindle, through 15 which said first thread is advanced, said winding head being secured to said tubular spindle to rotate therewith, said winding head comprising a rotatable housing member and cover, means for mounting the spool 20 of said second thread coaxially with said first thread to rotate with respect to said spindle within said rotatable housing member and cover, means for guiding said second thread at the point where it is about to be 25 wound about said first thread, means rotatable with said housing for guiding said second thread as it is unwound from said spool, said cover being conical in form and tapering from said second guide means to 30 said first guide means, said housing member being conical and tapering upwardly from the lower periphery of the spool to said second guide means.

4. A machine comprising means for advancing a thread longitudinally, and means 35 for wrapping a second thread about said first thread when said first thread is advanced, said wrapping means comprising a rotatable winding head for inclosing a mass 40 of said second thread, said rotatable winding head comprising a housing member and a cover member for said housing member, said cover member being conical in form and coaxial with said winding head, said 45 cover tapering away from said housing whereby centrifugal force will cause a current of air to flow downwardly along said cover to hold said cover in place on said housing member.

5. A machine comprising means for advancing a thread longitudinally, means for wrapping a second thread about said first thread, as said first thread is advanced, said wrapping means comprising a winding 55 head, said winding head comprising a housing member and a cover, and means whereby centrifugal force is exerted to hold said cover in place.

6. A machine comprising means for advancing a thread longitudinally, means for

wrapping a second thread about said first thread, as said first thread is advanced, said wrapping means comprising a winding head, said winding head comprising a housing member and a cover, and means whereby 65 centrifugal force is exerted to hold said cover in place, said last means comprising an eccentrically located latch member positioned so that centrifugal force tends to move it to latching position. 70

7. A machine comprising means for advancing a thread longitudinally, means for wrapping a second thread about said first thread, as said first thread is advanced, said wrapping means comprising a winding head, said winding head comprising a housing member and a cover, and means whereby 75 centrifugal force is exerted to hold said cover in place, said last means comprising an eccentrically located spring latch member, positioned so that centrifugal force tends to move it to latching position. 80

8. A machine comprising means for advancing a thread longitudinally, means for wrapping a second thread about said first 85 thread, as said first thread is advanced, said wrapping means comprising a winding head, said winding head comprising a housing member and a cover, and means whereby centrifugal force is exerted to hold said 90 cover in place, said last means comprising an eccentrically located latch member positioned so that centrifugal force tends to move it to latching position, said latch member comprising a spring finger. 95

9. A machine comprising means for advancing a thread longitudinally, means for wrapping a second thread about said first thread, as said first thread is advanced, said wrapping means comprising a winding head, said winding head comprising a housing member and a cover, and means comprising a spring finger latch to hold said 100 cover in place.

10. A machine comprising means for advancing a thread longitudinally, means for wrapping a second thread about said first thread, as said first thread is advanced, said wrapping means comprising a winding head, said winding head comprising a housing member and a cover, said cover having an opening therein, and means comprising a spring finger latch engaging the edge of the opening in said cover to hold said cover in place. 105 110 115

In witness whereof, we have hereunto subscribed our names.

REUBEN B. BENJAMIN.
JAMES M. CURLESS.
